R. Hamilton

INVENTOR.
William J. Haynes,
BY
Warren D. House,
His ATTORNEY.

UNITED STATES PATENT OFFICE.

WILLIAM J. HAYNES, OF KANSAS CITY, MISSOURI, ASSIGNOR OF ONE-HALF TO JOSEPH H. SWATHMEY, OF HARRISONVILLE, MISSOURI.

FLOAT.

Application filed December 30, 1926. Serial No. 157,960.

My invention relates to improvements in floats. It is particularly well adapted for use as an amusement device for taking swimming exercises, but it is also adapted for use 5 as a life preserver.

One of the objects of my invention is to provide a float of the kind described, which is simple, cheap, durable, strong, not liable to get out of order, which may be readily 10 and quickly assembled for use or disassembled for storage or shipment in compact form, which is safe, and which is adapted for use by old or young.

The novel features of my invention are 15 hereinafter fully described and claimed.

In the accompanying drawing, which illustrates my invention,

Fig. 1 is a plan view of my improved float in the preferred embodiment thereof.

20 Fig. 2 is a sectional view of the same on the line 2—2 of Fig. 1.

Fig. 3 is a cross section on the line 3—3 of Fig. 1.

Fig. 4 is a perspective of one of the tube 25 engaging members.

Fig. 5 is a plan view of a modification which employs but a single inflated tube.

Similar reference characters designate similar parts in the different views.

30 Referring to Figs. 1 to 4, 1 designates two air filled annular tubes, preferably of the type employed as inner tubes in automobile tires provided each with a filling tube 2 of usual type.

35 In use the tubes 1 are disposed in elliptical form and have respectively mounted in them two pairs of substantially semicircular members 3, each of which is provided in its arcuate edge with an arcuate groove 4 adapted

40 to receive the tube in which it is mounted. The opposite edge of each member 3 is provided with two grooves 5 and 6 disposed transversely to each other, the groove 5 being transverse to the plane of the groove 4 and having a recess 7, Fig. 4.

Two cross bars 8 and 9 have one set of ends respectively mounted in the grooves 5 of one pair of members 3, the other set of ends of the bars being respectively mounted 50 in the grooves 5 in the other members 3. Each of the bars 8 and 9 is provided with two dowel pins 10 adapted to fit in the recesses 7 of the grooves 5 in which the bar is mounted.

55 The inner edge of the bar 9 is provided

with a recess 9' adapted to receive one end of a center board 11, the other end of which extends through a slot 12 in the cross bar 8. The latter is provided with a transverse hole 13 intersecting the slot 12 adapted to receive a bolt 14, which is adapted to be extended through any of a longitudinal row of holes 15 in the center board 11. The bolt 14 may have on it a nut 16 for holding the bolt in its operative position, Figs. 1 and 2. The board 11 may have in its edges two hand hold notches 17. After the members 3 have been assembled with the cross bars 8 and 9, the center board 11 and the bolt 14, as above described, the tubes 1 are inflated. The float 70 will now be ready for use, the person using it lying on the center board between the tubes 1.

In the form shown in Fig. 5, but one tube 1 is used, it having mounted in it two of the members 3, as in the other form of my invention. The ends of the center board 11 are then respectively fitted in the grooves 6, the tube being inflated after the parts are assembled.

I do not limit my invention to the structure shown and described, as many modifications, within the scope of the appended claims, may be made without departing from the spirit of my invention.

What I claim is:—

1. A float of the kind described comprising two annular inflatable tubes, two pairs of peripherally grooved members respectively mounted in said tubes with the tubes fitted in the grooves of said members, two cross bars respectively connected to the members of opposite pairs, and a center board connecting said cross bars between said tubes.

2. A float of the kind described comprising two annular inflatable tubes, two pairs of peripherally grooved members respectively mounted in said tubes with the tubes fitted in the grooves of said members, two cross bars respectively connected to the members of opposite pairs, one of said cross bars having in its inner edge a recess, a center board having one end seated in said recess, and a bolt extending through said board and the other cross bar.

3. A float of the kind described comprising two annular inflatable tubes, two pairs of peripherally grooved members respectively mounted in said tubes with the tubes fitted in the grooves of said members, two cross

bars respectively engaging said members of opposite pairs, a center board having one end bearing against and supported by one of said cross bars and having a longitudinal 5 row of transverse holes, and a bolt extending through the other cross bar and adapted to be extended through any of said holes.

4. A float of the kind described comprising two annular inflatable tubes, two pairs of 10 members each having in one edge a peripheral arcuate groove and in its opposite edge a transverse groove provided with a recess, said pairs of members being mounted respectively in said tubes with said tubes mounted 15 in said arcuate grooves, two cross bars fitted respectively in the transverse grooves of said members, each cross bar having two dowel pins respectively fitted in the recesses of the adjacent ones of said members, one of said 20 cross bars having a recess in its inner edge, a center board fitted at one end in said edge recess of said cross bar and having a longitudinal row of holes, and a bolt extending through the other cross bar and adapted 25 to be extended through any of said holes.

5. In a float of the kind described, two pairs of members each having in one edge an arcuate groove adapted to have an inflated tube fitted therein, and having in its 30 other edge a transverse groove having a recess, two cross bars adapted to be respectively fitted in opposite ones of said pairs and provided each with two dowel pins

adapted to be fitted in the recesses of the adjacent members, one of the cross bars having an edge recess, the other bar having a transverse hole, a center board adapted to have one end fitted in said edge recess and having a longitudinal row of holes, and a bolt adapted to be extended through the hole in said 40 cross bar and through any of said holes in said center board.

6. In a float of the kind described, a member having in one edge an arcuate groove adapted to receive an inflated tube, and in 45 its opposite edge having a transverse groove having a recess and adapted to receive a cross bar having a dowel pin adapted to be inserted in said recess.

7. In a float of the kind described, a member having in one edge an arcuate groove adapted to receive an inflated tube, and in 50 its opposite edge having a recess parallel with the plane of said groove and adapted to receive one end of a center board.

8. In a float of the kind described, a member having in one edge an arcuate groove adapted to receive an inflated tube, and in 55 its opposite edge having two grooves transverse to each other and adapted to respectively receive the end of a center board and a cross brace.

In testimony whereof I have signed my name to this specification.

WILLIAM J. HAYNES.
